Pat. James Claude Mullins Inventor

UNITED STATES PATENT OFFICE

137,027

DESIGN FOR A BADGE OR SIMILAR ARTICLE

James Claude Mullins, St. Petersburg, Fla.

Application October 27, 1943, Serial No. 111,509

Term of patent 3½ years

To all whom it may concern:

Be it known that I, James Claude Mullins, a citizen of the United States, residing at St. Petersburg, in the county of Pinellas and State of Florida, have invented a new, original, and ornamental Design, for Badge or Similar Article, of which the following is a specification, reference being had to the accompanying drawing, forming part thereof.

I claim:

The ornamental design for a badge or similar article, as shown.

JAMES CLAUDE MULLINS.
